HAIR CLIP

Franklin C. Ghisletta, Patterson, Calif.

Application February 24, 1947, Serial No. 730,590

2 Claims. (Cl. 132—50)

1

My invention relates to a small device for dressing hair in tresses on a woman's head in order to hold the hairs together during and after dressing. The main object of this invention is to provide a clip of this kind which, when in use, will have a firm grip on the hair, so as not to fall off like ordinary hair pins, but remain in position on the head after the hair has been arranged by the wearer herself or by a hair dresser.

This hair clip can be manufactured at low costs from flexible material.

One embodiment of this invention is illustrated in the drawing wherein like numerals denote the same details in the different views.

Figure 1 is a perspective view of the hair clip in closed position;

Figure 2 is a side elevation of the clip open; and

Figure 3 is a plan view of the clip closed.

This clip consists of a base member 10, and a top member or shank 11, made in one piece of metal wire joined together to form a rounded head 12 which provides a hinge connection between the two members 10 and 11. The top member or shank 11 is straight at the first one third portion 13 thereof, which is situated nearest the head 12. The middle portion 14 is corrugated in a vertical plane while its end 15 again is straight terminating with a short upturned nose portion 16.

The base member 10 has also a straight portion 17 of about the same length as portion 13. The remainder of the base member is split or divided into a right and a left arm 18 and 19 which are flattened and preferably knurled to form finger grips. The remainder of the base member constitutes a loop 20, the left side of which is bent inwardly or kinked at 21 to form a catch for holding the nose of the top shank 11.

In its open position, as seen in full lines of Figure 2, the hair clip is ready for application. By taking hold of the instrument between the thumb and the second finger, pressing slightly on the flat arms 18 and 19, while the shank 11 is raised up between the thumb and first finger by an upward pull on the first finger, a lock of hair is entered in the gap between the shank 11 and the

2

base 10, care being taken that the hair is well spread out flat under the undulated or corrugated portion 14. Thereupon pressure is applied by the fore finger on shank 11 until the nose 16 is stopped by the loop 20 as shown in dotted lines, Figure 2, and lastly the nose 16 is pushed sideways under the kink 21, thereby locking the shank and base together over the enclosed hair see Figure 1. The corrugations 14 on the shank 11 will then prevent any hair from slipping in the hair grip.

The fact that the nose 16 points upwardly and the loop 20 points downwardly, aids in entering the hair clip amongst the hair and facilitates its application.

It is to be understood that the invention as herein disclosed may be varied from the details described and shown without departure from the spirit of the subjoined claims.

I claim:

1. A hair clip adapted for holding tresses of hair in order after dressing, comprising a long shank and a long base made of spring wire forming a unit with a connecting head holding said shank and base apart, the shank at its free end terminating in an upturned nose, said base being divided at approximately midway of its ends into a long two armed loop, and means at the outer end of the two armed loop forming a keeper for engagement by said nose to secure said shank in closed position.

2. A hair clip of the character described in claim 1 wherein the said keeper engaged by the shank nose consists of a kinked portion at the free end of said loop.

FRANKLIN C. GHISLETTA.
